United States Patent Office.

GEORGE H. PEACOCK, OF FAIRPORT, NEW YORK.

Letters Patent No. 76,941, dated April 21, 1868.

IMPROVED BAG-FASTENER.

The Schedule referred to in these Letters Patent and making part of the same.

TO ALL WHOM IT MAY CONCERN:

Be it known that I, GEORGE H. PEACOCK, of Fairport, in the county of Monroe, in the State of New York, have invented new and useful Improvements in Bag-Fasteners; and I do hereby declare that the following is a full and exact description of the same, reference being had to the accompanying drawings, and to the letters of reference marked thereon, making a part of this specification.

The nature of my invention consists in constructing bag-fasteners with the band A composed of metallic cord, the elasticity of such band admitting of sufficient opening or separation of its ends, so as to be readily placed around the neck of the bag; further, in providing said band with clasps, B B, these clasps being provided with hook C, and slot D, standing transversely to said hook, for the purpose of securing the fastening. The clasps B B are also provided with arms, E E, for facilitating the pressing of the fastener around the bag-neck; still further, in providing the outer ends of said arms, also the opposite parts or ends of the clasps, with ears or flattened projections, F F and G G, for the purpose of turning reversely the opposite parts of the clasp, thus enabling the opening and closing of said clasps.

I claim the band A, composed of metallic cord, in connection with the clasps B B, and fastenings C D, arms E E, and ears or projections F F and G G, all arranged to operate as herein set forth.
